BEAM-LOCKING DEVICE FOR LOOMS.

1,312,269.

Specification of Letters Patent.

Patented Aug. 5, 1919.

Application filed November 29, 1918. Serial No. 264,518.

To all whom it may concern:

Be it known that I, ALONZO E. RHOADES, a citizen of the United States, residing at Hopedale, county of Worcester, State of Massachusetts, have invented an Improvement in Beam-Locking Devices for Looms, of which the following description, in connection with the accompanying drawing, is a specification, like characters on the drawing representing like parts.

This invention relates to improvements in beam-locking mechanism for looms and the object thereof is to provide a simple and effective construction which will permit the beam shaft to be quickly introduced into its bearings in the loom sides and effectively locked therein.

In the usual loom construction the shaft of the warp beam is journaled in open bearings in the loom sides and is usually held therein by some sort of locking device which engages the shaft at the open side of the bearing.

In the operation of the loom considerable wear occurs upon the journal of the warp beam and journal, which permits a vibration or jump of the heavy warp beam to take place, particularly when the lay beats up. This is undesirable because of the effect upon the tension of the warp and consequently upon the cloth being woven.

The present invention is designed to provide for more securely retaining the beam shaft in proper position and to reduce the wear of the journals and journal bearings. This is accomplished by providing the loom sides with alined journal bearings, having openings in their walls to permit the introduction of the beam shaft, of less width than the diameter of the bearings, equipping the beam shaft with journals of greater diameter than the said shaft and complementary to said journal bearings, so that the beam shaft may be inserted sidewise into the bearings in the loom sides and the journals upon said shaft then inserted endwise into the journal bearings. It will be obvious that when the journals upon the shaft are thus inserted their diameter, being greater than the width of the aperture in the journal bearings, will prevent the removal of the shaft while permitting their own rotation in the bearings.

The further object of the invention is to provide a beam lock of the character above

described, which may be applied to the usual type of loom without material modification. This is accomplished in the present invention by providing brackets to be secured to the loom sides with journal bearings of the character above described, so that when the brackets are secured to the loom side, with the journals in axial alinement with the usual journals or seats in the loom sides, the shaft of the warp beam may be readily introduced into the bearings and locked therein by suitable journals slidably mounted upon the beam shaft and adapted to be inserted endwise into the journal bearings of the brackets.

A further feature of the invention consists in providing means whereby the bracket with the complementary journal bearing may be adjusted so that no difficulty will be experienced in causing axial alinement between the journal bearing of the bracket and the usual journal bearing in the loom side, the adjustment further permitting the taking up of any play in the bearing which may occur by reason of the wear of journal or journal bearing.

Other objects and features of the invention will more fully appear from the following descriptions and accompanying drawings and will be pointed out in the annexed claims.

In the drawings:

Figure 1 is a side elevation, of a portion of a loom, illustrating a preferred form of my invention applied thereto.

Fig. 2 is a rear elevation of a portion of the loom side, one end of the warp beam and its shaft and the means of locking the shaft in the loom side.

Fig. 3 is a detail view of the preferred form of bracket, having a journal bearing for the beam shaft and an aperture in its wall to permit the introduction of the shaft.

Fig. 4 is a detail view of the bracket having a journal bearing of the character shown in Fig. 3, and showing the beam shaft in said bracket and the journal upon said shaft removed from engagement with the journal bearing as if the shaft were about to be removed.

Fig. 5 is an end elevation of a split sleeve forming a journal for the shaft having lateral extensions adapted to be secured together.

The loom structure to which the present

invention is applied may be used in the usual character, comprising loom sides 1, 2 having extensions which provide shoulders 3, which have the usual sockets 4 to receive the shaft of the warp beam when the same is hoisted into preliminary position, and open journal bearings 5 to support the shaft of the warp beam in its normal position.

The warp beam 6 is of the usual character, having an attached ring gear 7 and a shaft 8 which is adapted to rest at its ends in the journal bearing 5 in the loom sides. The warp 9 from the warp beam is carried over the usual whip roll 10 to the shed in the usual manner.

Means are provided for permitting the introduction of the shaft into its bearing and for locking the shaft in said bearing by mechanism upon or carried by the shaft itself. In the preferred embodiment of the invention disclosed herein, the journal bearings for the shaft are made larger than the diameter of the shaft and their walls are provided with apertures through which the shaft may be introduced into the bearings. The shaft is provided with a journal of larger diameter than the shaft and complementary to the journal bearing. Means are provided for permitting end-wise movement of the journals upon the shaft to enable them to be fitted into the journal bearings, since the journal upon the shaft is of greater diameter than the opening through which the shaft is introduced sideways into the bearing.

It will be understood that journal bearings of this character may be formed directly in the loom sides but preferably are carried by brackets adapted to be secured to the loom sides and having journal bearings of greater diameter than the shaft adapted to be placed in axial alinement with the usual bearings in the loom sides.

In the preferred embodiment of the invention disclosed in the accompanying drawings, a bracket 11 is adjustably secured to each loom side by a bolt 12 passing through a slot in said bracket, and a suitable aperture in the loom side. The bracket 11 has a lateral extension 14 provided with a cylindrical boss 15 forming a journal bearing 16. A portion of the wall of the boss 15 is cut away to form an aperture 17 of slightly greater width than the diameter of the shaft 8. When the bracket is secured to the loom side the opening 17 lies opposite the open portion of the usual journal bearing in the loom side so that the shaft may be introduced into the bearings in the usual manner. The journal bearing 16 in the bracket 11 is of considerably larger diameter than the diameter of the shaft 8, and in the preferred embodiment of the invention the shaft is supported within the bearing 16 by a journal 18 carried by the shaft 8 and adapted to be

inserted endwise into the journal bearing 16. It will be obvious that when the journal 18 is inserted in the journal 16 the shaft will be prevented from removal from said bearing because the journal 18 is of too large a diameter to pass through the opening 17 through which the shaft was introduced.

The journal 18 desirably is in the form of a split sleeve, having lateral extensions 19—20, secured together by bolts or screws 21, so that the sleeve may be clamped upon the shaft 8. By reason of this construction the loosening of the screws 21 will permit the sleeve to slide along the shaft so that it may be readily inserted endwise into the journal bearing 16. When the screws 21 are set up they will lock the sleeve upon the shaft with the journal 18 properly mounted within the journal bearing 16. When the parts are thus assembled at both ends of the shaft any endwise movement of the shaft during the rotation of the warp beam will be prevented, since such end-wise movement would cause the end 22 of one of the bosses 15 to come in contact with a shoulder 23 upon one of the extensions 19 of said split sleeves.

In the preferred construction the journals 18 are adjustably secured upon the shaft 8 at both ends, but it will be obvious that if desirable an enlarged journal complementary to the journal bearing 16 may be permanently secured to or made integral with the shaft 8 and introduced into the journal bearing 16 by endwise movement of the shaft. In view, however, of the heavy weight of the warp beam such construction is undesirable and is mentioned only for the purpose of emphasizing the fact that the preferred embodiment of the invention disclosed herein is merely illustrative and restrictive and that various modifications may be made within the meaning and scope of the following claims.

Having thus described my invention what I claim as new and desire to secure by Letters Patent is:

1. In a loom, beam-locking mechanism comprising alined journal bearings upon the loom sides, having openings in their walls to permit the introduction of the beam shaft and means carried by said shaft operable to prevent removal of the shaft from said journal bearings.
2. In a loom, beam-locking mechanism comprising alined journal bearings upon the loom sides, having openings in their walls to permit the introduction of the beam shaft, but of less width than the diameter of said bearings and journals upon the shaft of greater diameter than the shaft and complementary to said bearings, capable of being inserted endwise into said journal bearings, after the shaft has been introduced therein, whereby removal of the shaft from the journal bearings will be prevented.

3. In a loom, beam-locking mechanism alined journal bearings upon the loom sides, having openings in their walls to permit the introduction of the shaft, but of less 5 width than the diameter of the bearings and journals upon said shaft of greater diameter than said shaft and complementary to said bearings slidably secured upon said shaft and capable of being inserted endwise into 10 said journal bearings after the shaft has been introduced therein.

4. In a loom, beam-locking mechanism comprising alined journal bearings upon the loom sides, having openings in their 15 walls to permit the introduction of the body of the shaft, but of less width than the diameter of the bearings and journals upon said shaft comprising split sleeves capable of being adjustably secured upon said shaft 20 and having journal portions complementary to the journal bearings adapted to be inserted therein by endwise movement.

5. In a loom having a warp beam and loom sides provided with alined bearings to 25 receive the shaft of the warp beam, brackets secured to the loom sides having journal bearings provided with openings in their 30 walls of less width than the diameter of said bearings, to permit the introduction of the beam shaft, journals upon said beam shaft complementary to said journal bearings adapted to be inserted endwise into said 35 journal bearings and means for securing said journals to said shaft.

6. In a loom having a warp beam and loom sides provided with alined bearings to receive the shaft of the warp beam, brackets having journal bearings provided with open-

ings in their walls of less width than the diameter of said bearings, means for adjustably securing said brackets to said loom sides to enable the bearings in said loom sides and said bracket to be placed in axial alignment, and journals complementary to the journal bearings of said brackets adjustably 45 secured to the beam shaft and adapted to be inserted endwise into said journal bearings.

7. Beam locking mechanism for looms comprising a bracket, having a journal bearing provided with an opening in its wall of less width than the diameter of the bearing, but greater than the diameter of the beam shaft, and a journal complementary to said journal bearing adapted to be secured 50 to said beam shaft, the journal being adapted to be inserted endwise into the journal bearing to provide a bearing for the beam shaft and to prevent removal of said shaft 55 from the bearing.

8. Beam locking mechanism for looms comprising a bracket, having a journal bearing provided with an opening in its wall of less width than the diameter of the bearing, but greater than the diameter of the beam 65 shaft, and a journal adapted to be secured to said beam shaft comprising a split sleeve, having a peripheral surface complementary to said journal bearing and laterally extending flanges and means securing said flanges 70 together to clamp said sleeve releasably upon said beam shaft.

In testimony whereof I have signed my name to this specification.

ALONZO E. RHOADES.
